(57) CLAIM

The ornamental design for a water painting board with case, as shown and described.

DESCRIPTION

FIG. 1 is a top front perspective view of a water painting board with case showing my new design;
FIG. 2 is a bottom rear perspective view thereof;
FIG. 3 is a front elevational view thereof;
FIG. 4 is a rear elevational view thereof;
FIG. 5 is a top plan view thereof;
FIG. 6 is a bottom plan view thereof;
FIG. 7 is a right elevational view thereof;
FIG. 8 is a left elevational view thereof;
FIG. 9 is a top front perspective view thereof, showing the water painting board with case in a closed configuration;
FIG. 10 is a bottom rear perspective view thereof;
FIG. 11 is a top front perspective view thereof, showing the water painting board with case in a stand configuration; and,
FIG. 12 is a bottom rear perspective view thereof.

The broken lines showing an elastic band in FIGS. 1-12, and the broken lines showing a logo in FIGS. 2, 4, 9, and 10 are included for the purpose of illustrating environmental structure and form no part of the claimed design.

1 Claim, 12 Drawing Sheets
